(57) **CLAIM**

The ornamental design for a baby carrier with a removable hood, as shown and described.

DESCRIPTION

FIG. 1 is front elevational view of a baby carrier with a removable hood showing my new design;

FIG. 2 is a rear elevational view thereof, shown in the opened condition;

FIG. 3 is a right side elevational view, shown in the closed position;

FIG. 4 is a left side elevational view thereof;

FIG. 5 is a top plan view thereof;

FIG. 6 is a bottom plan view thereof; and,

FIG. 7 is a top, front perspective view of the removable hood of FIG. 1, shown in an enlarged scale, in the detached condition.

The dashed lines shown on the drawing views represents a stitching line.

The stippled shading shown on the FIG. 2 and 7 drawing views represents a textured fastening device.

The oblique line shading shown on the rectangular detail of the removable hood represents a transparent material.
